Primary Examiner — T. Chase Nelson*Assistant Examiner* — Mark Cavanna(74) *Attorney, Agent, or Firm* — Sand & Sebolt(57) **CLAIM**

The ornamental design for a beaker, as shown and described.

DESCRIPTION

FIG. 1 is a perspective view of the beaker in accordance with my design;

FIG. 2 is a front elevational view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a perspective view of a base of the beaker of FIG. 1;

FIG. 9 is a front elevational view thereof;

FIG. 10 is a right side view thereof;

FIG. 11 is a rear view thereof;

FIG. 12 is a left side view thereof;

FIG. 13 is a top view thereof;

FIG. 14 is a bottom view thereof;

FIG. 15 is a cross-sectional view thereof taken along line 15-15 of FIG. 13;

FIG. 16 is a perspective top view of a lid of the beaker of FIG. 1;

FIG. 17 is a top view thereof; and,

FIG. 18 is a front view thereof.
